UNITED STATES PATENT OFFICE.

FREDERICK H. PERRY, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

METHOD OF CHANNELING SHOE-SOLES.

1,272,709.

Specification of Letters Patent. Patented July 16, 1918.

Original application filed September 25, 1916, Serial No. 122,004. Divided and this application filed December 7, 1916. Serial No. 135,584.

To all whom it may concern:

Be it known that I, FREDERICK H. PERRY, a citizen of the United States, residing at Beverly, in the county of Essex and Commonwealth of Massachusetts, have invented certain new and useful Improvements in Methods of Channeling Shoe-Soles; and I do hereby declare the following to be a full, clear, and exact description of the invention, 10 such as will enable others skilled in the art to which it appertains to make and use the same.

The invention relates to a method of channeling shoe soles, and to the sole channeled 15 thereby.

This application is a division of application Serial No. 122,004, filed September 25, 1916.

It has been customary in channeling the 20 outsoles of shoes to cut the channel a uniform depth throughout, and at a greater distance from the edge of the sole through the shank than about the forepart, the edge of the sole being trimmed or chamfered off 25 up to the edge of the channel flap in finishing the shoe after the outsole has been sewed thereto. In doing certain classes of work the trimming or chamfering of the edge of the sole along the shank is objectionable. 30 For instance, in making shoes having thin edge shanks in which the sole edge is reduced in thickness by skiving the outsole outside the bottom of the channel through the shank, the subsequent trimming of the 35 sole edge tends to nullify the effect of the skiving.

It is the primary object of the present invention to so channel the sole that comparatively little cutting away or trimming of its edge will be required in the edge 40 finishing operations. The invention accordingly contemplates cutting a channel of varying depth a uniform distance from the sole edge, the channel being deeper and 45 the channel flap correspondingly broader through the shank than about the forepart.

The bottom of the channel may thus be located at the proper increased distance from the sole edge through the shank, and 50 at the same time a channel flap will be provided of sufficient breadth to extend substantially to the sole edge, so that little trimming is required to finish the sole edge

after the channel flap is laid. The invention also contemplates skiving or beveling 55 the edge of the sole to form a thin edge shank, and in such case the broad channel flap is especially important, since it will properly cover the outsole, and since the thickness of the skived sole edge need not be 60 materially increased by the subsequent edge finishing operations.

The invention as outlined above is illustrated in the accompanying drawings, in which Figure 1 shows the bottom of an outsole channeled in accordance with the invention, and Fig. 2 is a fragmentary sectional view on line 2 of Fig. 1.

The outsole shown in the drawings is provided about its edge with a channel 2 of 70 varying depth, which is cut at a uniform distance from the edge of the sole to form a channel flap 4, the width of which varies in accordance with the depth of the channel. Since the bottom of the channel of an outsole should be at a greater distance from the edge of the sole through the shank than about the forepart, the channel is cut to a uniform depth about the forepart, and is cut to an increased depth through the shank. 80 The channel may be cut by any suitable means or mechanism, as for instance by the machine shown and described in the application above referred to. If cut on a channeling machine, or on a rounding and channeling machine, the channel knife or knives should be constructed and operated to cut the deep channel and broad channel flap through the shank to decrease the depth of 85 channel and width of channel flap in passing from the shank to the forepart, and to increase the depth of the channel and breadth of the channel flap in passing from the forepart into the shank at the other side of the sole.

In manufacturing shoes having thin edge shanks, the edge of the sole outside of the bottom of the channel and under the channel flap is cut away or skived to form a bevel edge, as indicated at 6 in Fig. 2. This may 100 be done at the same time the deep channel is cut, or subsequently.

The above method of channeling the sole provides a broad channel flap through the shank which reaches substantially to the 105 edge of the sole, so that no more trimming

is required in finishing the sole edge through the shank than about the forepart, and in the case of a sole having a skived or beveled edge, the flap is broad enough to reach down over and be securely cemented to the inclined surface of the sole.

Having explained the nature and object of the invention, and specifically described one application thereof, what is claimed

10 is:

1. The method of channeling shoe soles consisting in cutting a channel of varying depth in the face of the sole a uniform distance from the sole edge.
- 15 2. The method of channeling shoe soles consisting in cutting a channel in the face of the sole about the sole edge and varying the depth of the channel and breadth of the channel flap along portions of the sole edge.
- 20 3. The method of channeling shoe soles consisting in cutting a channel in the face of the sole about the sole edge and increasing the depth of channel and breadth of the channel flap through the shank.
- 25 4. The method of channeling shoe soles

consisting in cutting a channel in the face of the sole about the sole edge and increasing the depth of channel and breadth of the channel flap, and reducing the thickness of the sole edge through the shank.

5. A shoe sole having in its face a channel of varying depth and a channel flap of correspondingly varying breadth about the sole edge.

6. A shoe sole having in its face a channel of varying depth and a channel flap the edge of which is a uniform distance from the sole edge.

7. A shoe sole having in its face a channel of greater depth through the shank than about the forepart, and a channel flap of correspondingly greater breadth through the shank.

8. A shoe sole having in its face a channel of greater depth through the shank than about the forepart, a channel flap of correspondingly greater breadth through the shank, and a beveled edge through the shank.

FREDERICK H. PERRY.
